(57) **CLAIM**

I claim the ornamental design for an outsole for a shoe, as shown and described.

DESCRIPTION

FIG. 1 is a bottom plan view of an outsole for a shoe showing my new design;

FIG. 2 is a right side elevational view thereof;

FIG. 3 is a left side elevational view thereof;

FIG. 4 is a front elevational view thereof;

FIG. 5 is a rear elevational view thereof; and,

FIG. 6 is a cross-sectional view taken on line 6—6 of FIG. 1; the broken lines showing the interior being understood to illustrate the portion of the design that forms no part of the claim, and the depths of the contoured grooves being understood to be uniform depth throughout the design.
